SUCTION CLEANER

Donald G. Smellie, Canton, Ohio, assignor to The
Hoover Company, North Canton, Ohio, a cor-
poration of Ohio

Application February 17, 1934, Serial No. 711,669

12 Claims. (Cl. 15—16)

The present invention relates to suction cleaners in general and particularly to new and novel improvements in suction cleaners by which the nozzle height can be adjusted by the operator 5 from the end of the propelling handle. More specifically the invention comprises the provision of a suction cleaner provided with a pivoted handle which incorporates manually operable means to raise and lower certain of the supporting wheels 10 of the cleaner for the purpose of adjusting the nozzle height relative to the surface covering undergoing cleaning.

It is an object of the present invention to provide a new and improved nozzle-height adjusting means. It is another object to provide a new and improved suction cleaner in which the nozzle height is adjustable by means positioned upon the cleaner handle. A still further object is the provision of a suction cleaner provided with a pivoted handle which includes manually operable means which permit the operator to adjust the nozzle height while standing upright. These and other more specific objects will appear upon reading the following specification and claims 25 and upon considering in connection therewith the attached drawings to which they relate.

Referring now to the drawings, in which a preferred embodiment of the invention is disclosed:

Figure 1 is a side elevation of a modern suction cleaner embodying the present invention;

Figure 2 is an enlarged top view of the cleaner proper shown in Figure 1 with certain parts broken away;

Figure 3 is a side elevation with certain parts broken away;

Figure 4 is a partial section upon the line 4—4 of Figure 3;

Figure 5 is a side view of the end of the cleaner handle, being shown partly in section;

Figure 6 is a side elevation of the manually operable height adjusting element carried by the cleaner handle;

Figure 7 is a section upon the line 7—7 of Figure 5;

Figure 8 is a transverse cross-section through the cleaner handle upon the line 8—8 of Figure 5;

Figure 9 is a section upon the line 9—9 of Figure 5.

The usual suction cleaner embodies means to 50 adjust the height of the cleaner nozzle relative to the surface covering undergoing cleaning which are positioned upon the body proper of the cleaner. Height-adjusting means for the nozzle are required because of the variation in the 55 various types of floor coverings. With one type

of floor covering the supporting means or wheels of the cleaner sink into the pile of the covering to a greater or lesser distance than in another type of covering. This difference causes the nozzle to be positioned at different elevations. Also, certain coverings are heavier than others and the nozzle must be positioned closer thereto in order that the suction can lift the covering from the supporting surface into contact with the nozzle lips so that the cleaning air entering the nozzle under the lips will pass through the pile of the covering. This lifting is also necessary where surface-agitating means are positioned within the nozzle as such means are adapted to function upon that part of the covering which is lifted from its contact with the supporting surface.

With the nozzle-height adjusting means positioned upon the body of the machine it is necessary for the operator to bend over each time he desires to adjust the nozzle height. In the suction cleaner constructed in accordance with applicant's invention means have been provided which makes possible the adjustment of the nozzle height with the operator standing upright. This is accomplished through providing a nozzle adjustment means including a manually operable element, positioned near the end of the cleaner handle, which is connected by power-transmitting means to the cleaner proper and so to the front supporting wheels which it is adapted to raise and lower.

Referring again to the drawings a modern suction cleaner is shown which comprises a nozzle 1, a fan chamber 2, an interconnecting passageway therebetween, indicated by the reference character 3, and an exhaust outlet 4 to which is attached the dust bag 5. A driving motor 6 is positioned within the motor casing 7 and carries upon the extended end of its shaft the suction-creating fan 8 in the fan chamber 2. The opposite end of the motor shaft is formed as a pulley 9 and is connected to a power-transmitting belt 10 which extends to the nozzle 1 through a channel or passageway 11. Within the nozzle 1, and rotatably supported, is an agitator 12 of a well known type including rigid beating elements and flexible brush elements. Agitator 12 is provided with a pulley surface 13 which connects with the belt 10 so that the rotation of the motor results in the rotation of the agitator.

The cleaner body is movably supported upon spaced pairs of front and rear supporting wheels 14, 14 and 15, 15, respectively, the rear wheels being fixedly and rigidly carried by the body of the machine while the front wheels are carried

pivoted upon a crank shaft 16 which is carried by suitable brackets 17, 17 on the under side of the cleaner body.

As in the usual suction cleaner of this type a handle 18 is provided which comprises an elongated hollow tubular member which is pivoted at its lower end to the cleaner body and which is provided at its upper end with a grip member 19 by which the operator grasps the handle when propelling the machine. The grip member 19 is preferably of insulating material, as the incoming power leads 20, 20 enter the handle at that point. These leads pass through a manually operable switch 21 which is conveniently located relative to the handle and immediately adjacent thereto, down the tubular handle body, and into the motor casing to be connected to the motor 6.

The lower end of the tubular member of the handle 18 seats within a pivoted forked socket member 21, being insulated therefrom by an inclosing insulating member 22. Member 21 is forked immediately below the socket portion and its arms 23, 23 inclose and seat upon a transversely extending hollow supporting shaft or axle, 24 which is itself rotatably mounted in spaced seats 25, 25 formed on the top of the cleaner body, and more specifically upon the top of the exhaust outlet 4 immediately behind the motor casing 7. The spaced arms 23, 23 of the socket member 21 extend along the outer sides of the seat members 25, 25, the shaft member 24 extending through the seats and then through the arms. The relationship is made permanent by means of a removable nut member 26 which seats in screw threaded relationship with one end of shaft 24 and clamps one of the arms 23 against an outwardly facing circular shoulder 27 formed on the shaft 24. The arm 23, being clamped to the shaft 24, causes that member to rotate as the handle is pivoted.

A spring-pressed plunger 28 is slidably positioned within the hollow shaft 24 and is resiliently urged to the end thereof to which the nut 26 is attached. The ends of the plunger are of reduced size, one end being square in cross-section, as indicated at 29, and extending through a similarly formed socket in its end of the enclosing shaft 24. This relationship prevents relative rotation between the plunger and its enclosing socket member. The opposite end of the plunger is formed as an elongated reduced element 30 and is surrounded by a spiral coiled spring 31 which contacts the plunger body 28 at its enlarged portion and, at its opposite end, 55 the closure nut member 32 seated in screw threaded relationship with the end of hollow shaft 24. The plunger 28 is also provided with a centrally positioned sloping cam face 33, for a reason which will hereinafter be made apparent.

The crank arm 16 is provided with a rigid up-standing lever arm 38 to which is pivotally connected a shaft or plunger member 34. The opposite end of shaft 34 pivotally connects to one side of a V-shaped lever element 35 which is pivoted at 36 closely adjacent the outer end of plunger 28. The opposite side of the V-shaped lever extends into contact with the end of the plunger. V-shaped lever 35 is held in contact with the outer end of plunger 28, outside the nut 32, by means of a coil spring 37 which is carried by the crank shaft 16 and which contacts the lever arm 38 and the cleaner body to move the shaft 34 in the direction of the V-shaped lever. Clearly the movement of plunger 28 to pivot the V-shaped lever 35 will result in the

raising and lowering of the nozzle wheels as its movement is directly transmitted to the crank shaft through the power-transmitting means just described.

To accomplish the pivotal movement of the V-shaped lever 35, and more directly the transverse movement of the plunger 28, there is provided near the top of the handle 18 an inclosing manually rotatable cylindrical member 40. Member 40 is internally screw threaded at 41 and incloses in screw-threaded relationship an element 42 which encircles the handle 18. The rotation of the member 40 functions to move it up or down the handle, the element 42 being rigidly secured to the handle. A rigid rod 43 extends down the handle 18 from the member 40, being provided at its lower end with a wedge member 44 which slidably seats within a seat 45 on member 21, and which extends through an opening 46 in hollow shaft 24 with its inclined end or wedge in contact with the cam face 33 of plunger 28. The angle of inclination of the cam face 33 of the plunger and of the inclined end of wedge 44 are the same so that they make line contact, forming in effect co-operating cams, the plunger being held in contact with the wedge through the action of its coil spring 31.

The upper end of rod 43 is carried by a block 47 which is exteriorly shaped to conform to the inner dimensions of handle 18 so that it can slide therein. Radially extending plugs 48, 48 extend through the handle 18 at longitudinally extending slots 50, 50 formed therein and into a circular internal channel or groove 51 formed in rotary member 40. Channel 51 is provided with an opening 52 at one point which permits of the removal of screws 49, 49, and so the plugs 48, 48, when aligned radially therewith.

An indicating mechanism is formed upon the handle which comprises a longitudinally extending opening 53 which is narrowed at a central point to indicate nozzle positions upon a slide member 54, carried by and movable with the rod 43 and the block 47. On the outwardly facing surface of slide 54 are marked the letters H, M, and L, which indicate that with the adjustment related so that the central pointer indicates one of the letters, the nozzle is "High," "Low" or "Medium."

The incoming power leads 20, 20 which enter the handle above the manually adjustable member 42 pass by the block 47, in a conduit 55 formed in one side of the handle, the block being recessed to accommodate the conduit. At the lower end of the handle the leads extend outwardly therefrom at the socket 21, a removable plug and socket construction 56 being provided at that point.

As in the usual cleaner construction handle-position-controlling means are provided and comprise an arcuate sector 57, carried rigidly by an arm 23 of the socket member 21, and a cooperating spring-pressed roller detent 58. The arcuate sector is so formed that the handle is resistingly retained in a vertical position, an intermediate range of movement, and in a horizontal position.

In the adjustment of the nozzle height of the suction height constructed in accordance with the present invention the operator rotates the manually rotatable member 40 which is conveniently positioned as described. Rotation of this member serves to move the rod 43 either up or down within the handle, the moving force being transmitted to the block by the legs 48, 48.

If the operator desires to place the nozzle in a high position, that indicated by the letter H in Figure 6, he rotates the element 40 so as to cause slide 54 to move downwardly to bring the letter H opposite the narrowed part of the slot 53. As the plunger 43 also moves downwardly with the slide the wedge 44 is advanced relative to the plunger 28. Plunger 28 is moved outwardly by the wedge resulting in the pivotal movement, in a counter-clockwise direction as viewed in Figure 2, of the V-shaped lever 35. Lever 35 functions to move shaft 34 towards the crank shaft and the lever arm 38, to which it is pivotally attached, is moved counter-clockwise, as viewed in Figure 2. This results in the downward movement of the crank shaft wheels and the raising of the nozzle.

To lower the nozzle the operation is exactly the reverse. Rotation of element 40 in the opposite direction results in the movement of rod 43 upwardly in the handle and the withdrawal of wedge 44 permits plunger 28 to move inwardly under the force exerted by spring 25. Coil spring 57 carried by the crank shaft 16 urges the crank shaft and the front supporting wheels 14, 14 to the uppermost position permitted by the contact of the V-shaped wedge 35 with the end of plunger 28.

30 I claim:

1. In a suction cleaner, a body including a nozzle, supporting wheels, means mounting said wheels on said body, a handle pivoted to said body, and means to adjust said wheels relative to said body to raise and lower said nozzle, said means comprising a plunger positioned at the pivotal axis of said handle, a longitudinally movable member extending through said handle from said plunger to a point near the upper end thereof, rotating means on said handle to move selectively said longitudinally movable member up or down said handle, and means connecting said plunger to said wheel-mounting means to adjust said wheels relative to said body upon movement of said plunger.

2. In a suction cleaner, a body including a nozzle, supporting wheels, means movably mounting said wheels on said body, a handle pivoted to said body, and means to adjust said wheels relative to said body to raise and lower said nozzle, said means including a longitudinally movable member carried by said handle, means to move said member, a member movable transversely to said handle in the pivotal axis of said handle and connected to said longitudinally movable member, and means connecting said transversely movable member to said wheel-mounting means to move same relative to said body upon movement of said transversely movable member.

3. In a suction cleaner, a body including a nozzle, supporting wheels, means movably mounting said wheels on said body, a handle pivoted to said body, and means to adjust said wheels relative to said body to raise and lower said nozzle, said means including a longitudinally movable member carried by said handle and provided with cam means at its lower end, a transversely movable member in the pivotal axis of said handle provided with cooperating cam means, and power-transmitting means connecting said transversely movable member to said wheel-mounting means to adjust said wheels relative to said body upon movement of said longitudinally movable member.

4. In a suction cleaner, a body including a

nozzle, supporting wheels, means movably mounting said wheels on said body, a handle pivoted to said body, and means to adjust said wheels relative to said body to raise and lower said nozzle, said means including a longitudinally movable rod in said handle provided with a wedging surface at its lower end, a manually rotatable member within the limits of said handle, cooperating means on said rotatable member and on said rod to move the latter longitudinally upon the rotation of the former, a transversely movable member in the pivotal axis of said handle in contact with said wedging surface and adapted to be moved thereby, and movement transmitting means connecting said transversely movable member to said wheel-supporting means to adjust said wheels relative to said body upon movement of said rod.

5. In a suction cleaner, a body including a nozzle, supporting wheels, means pivotally mounting said wheels on said body, a handle, means pivotally mounting said handle on said body, said last-mentioned means including a hollow shaft at the pivotal axis, a spring-pressed plunger in said shaft, a longitudinally movable element extended through said handle, cooperating means to move said plunger against the force exerted by said spring upon the movement of said longitudinally movable element, and power-transmitting means between said plunger and the mounting means for said wheels to pivot the latter upon the movement of the former.

6. In a suction cleaner, a body including a nozzle, supporting wheels, a crank shaft pivotally mounting said wheels on said body, a handle pivotally mounted on said body, a manually rotatable member at the upper end of said handle, a rod extended through said handle and movable longitudinally upon the rotation of said member, a transversely slid able member in the pivotal axis of said handle, a wedge at the lower end of said rod in contact with said slid able member to exert a moving force thereon upon the movement of said rod, a lever contacting said slid able member, a shaft pivotally connected to said lever and moved by the movement thereof, and a lever carried by said crank shaft to which the opposite end of said shaft is pivoted and which is actuated by the movement of said shaft, said levers and shaft functioning to pivot said crank shaft upon the movement of said slid able member.

7. In a suction cleaner, a body including a nozzle, supporting wheels, means mounting said wheels for vertical movement relative to said body to adjust the height of said nozzle, a handle pivotally mounted on said body, means to raise and lower said wheels relative to said body including a manually operable member at the upper end of said handle, and means to indicate the height of said nozzle relative to the supporting surface comprising a stationary indicating means carried by said handle and a movable element actuated by said manually operable member.

8. The construction recited by the preceding claim characterized by the fact that said indicating means is a pointer formed at a longitudinally extending slot in said handle and said movable element comprises a longitudinally slid able member in said handle and under said slot which is provided with markers upon its exposed surface which markers move toward and from said pointer as the slid able member is moved.

9. In a suction cleaner, a body including a nozzle, supporting wheels, means movably mounting

said wheels on said body, a handle pivoted to said body, a member slidably in the pivoted axis of said handle, manually adjustable means on said handle to move said member longitudinally of said pivoted axis, and means cooperating with said member to move said mounting means relative to said body upon the movement of said member.

10. In combination in a suction cleaner, a body having a nozzle, adjustable means to position said nozzle relative to a surface covering undergoing cleaning, a handle connected to and extended from said body adapted to receive a propelling force, stationary nozzle-height-indicating means carried by said handle positioned at a distance from said body, movable nozzle-height-indicating means carried by said handle and positioned in cooperative relationship to said stationary means, and means interconnecting said movable nozzle-height-indicating means to said adjustable means and adapted to move the former as the latter is adjusted.

15. In combination in a suction cleaner, a body having a nozzle, adjustable means to position said body relative to a surface covering undergoing cleaning, a hollow handle connected to and ex-

tended from said body and adapted to receive a propelling force, said handle being formed with an aperture at a point spaced from said body, moveable body-position-indicating means mounted in said handle at said aperture, and means extended downwardly through said handle from said indicating means and operatively connected to said adjustable means and adapted to move said indicating means upon adjustment of said adjustable means.

20. In combination in a suction cleaner, a body including a nozzle, adjustable means to position said nozzle relative to a surface covering undergoing cleaning, a hollow handle pivotally connected to said body and adapted to receive a propelling force, said handle being formed with an aperture at a point spaced from said body, moveable nozzle-height-indicating means mounted in said handle at said aperture, means extending through said handle to its pivot point connected to and adapted to move said indicating means, and means connected to said adjustable means and to said means extended through said handle to transmit movement therebetween.

25

DONALD G. SMELLIE.
